(57) **CLAIM**

The ornamental design for a foot hold apparatus for sit-ups, as shown and described.

DESCRIPTION

FIG. 1 is a perspective view of a foothold apparatus for sit-ups, of the present invention;

FIG. 2 is a front view of a foot hold apparatus for sit-ups of FIG. 1;

FIG. 3 is a rear view of a foot hold apparatus for sit-ups of FIG. 1;

FIG. 4 is a left side view of a foot hold apparatus for sit-ups of FIG. 1;

FIG. 5 is a right side view of a foot hold apparatus for sit-ups of FIG. 1;

FIG. 6 is a top view of a foot hold apparatus for sit-ups of FIG. 1; and,

FIG. 7 is a bottom view of a foot hold apparatus for sit-ups of FIG. 1.

1 Claim, 7 Drawing Sheets

FIG. 1

FIG. 2

FIG. 3

FIG. 4

FIG. 5

FIG. 6

FIG. 7
